UNITED STATES PATENT OFFICE.

JAMES B. ARTHUR, DECEASED, BY MARY R. ARTHUR, EXECUTRIX, OF JOPLIN,
MISSOURI.

ORE CONCENTRATOR.

1,416,928.

Specification of Letters Patent. Patented May 23, 1922.

Application filed February 21, 1920. Serial No. 360,434.

To all whom it may concern:

Be it known that I, MARY R. ARTHUR, a citizen of the United States, residing at Joplin, in the county of Jasper and State of Missouri, have been appointed executrix of the last will and testament of James B. Arthur, late a citizen of the United States, deceased, who invented certain new and useful Improvements in Ore Concentrators, of 10 which the following is a specification.

My invention relates to ore concentrators and is an improvement on the ore concentrator disclosed in U. S. Letters Patent No. 722,933, and bearing date of March 17, 1903.

15 One object of the present invention is to provide means for feeding the crushed ore in a more uniform manner than heretofore to the rotary table upon which the concentrates are collected.

20 Another object is to provide means for draining off the surplus water admitted to the table with the crushed ore.

Other objects will hereinafter appear and in order that the invention may be fully 25 understood, reference will now be had to the accompanying drawings, in which:

Fig. 1 is a broken side elevation of the machine.

Fig. 2 is an enlarged broken vertical section on line II—II of Fig. 6.

Fig. 3 is an enlarged vertical, fragmentary section of a gate and associated parts.

Fig. 4 is an enlarged broken cross section on line IV—IV of Fig. 6.

30 Fig. 5 is a detail plan view of a star wheel employed in carrying out the invention.

Fig. 6 is a front elevation of the machine with some of the mechanism removed and a sweep in position for packing down and 40 smoothing the material as it enters upon the table.

Referring now in detail to the various 45 parts, 2 designates a suitable frame, in the center of which a vertically-disposed shaft 4 is mounted. Said shaft 4 is journaled at its upper portion in a bearing 6 and at its lower end in a step bearing 8.

50 10 designates a rotary table having a centrally-disposed hub 12 keyed or otherwise fixed to the shaft 4 in order to rotate therewith. Said table 10 has a circular portion 14, preferably, of slightly conical form and surmounted by a rim 16, having a plurality of ports 18 for the discharge of surplus 55 water entering with the crushed ore.

The ports 18 are fitted with rectangular frames 20 having vertical grooves 22 to receive vertically movable gates 24 equipped at their upper ends with spouts 26. The lower portion of each gage 24 is equipped 60 with a nut 28 to travel up and down on a screw 30 journaled in a bracket 32 fixed to the underside of the table 10. The lower end of the screw 30 is equipped with a star wheel 34, which is fixed to said screw 30 to 65 rotate the same.

36 designates a lever mounted on a pivot 38 fixed to a standard 40. The lever 36 has upwardly-extending prongs 42 and 44, one of which when thrown into the path of the star 70 wheel 34 rotates the same in a direction to cause the screw 30 to raise the gage 24, while the other prong when thrown into the path of said star wheel rotates the same in a reverse direction to lower the gate 24. The 75 lever 36 is held in the neutral position disclosed by Fig. 3, or in position to hold either of its prongs in the path of the star wheel 34, by a pin 46 adapted to enter any of the openings in a segment 48 secured to 80 the standard 40.

The table 10 is provided with a fixedly-mounted, centrally-disposed drum 50, which is surmounted by a conical distributor 52 fixed to the lower end of a tubular shaft 54, 85 journaled on the shaft 4 and resting upon a collar 56 fixed to said shaft 4. The margin of the distributor 52 is surrounded by an annular guard 58 supported by arms 60 secured to the periphery of the drum 50. As 90 shown more clearly on Fig. 2, the guard 58 is spaced from the circular margin of the distributor 52 to leave an annular space for the passage of the crushed ore from said distributor 52 to the table 10. 95

62 designates a rotary hopper disposed above the distributor 52 and supported by arms 64, adjustably connected at their upper ends to a sleeve 66 having a groove and feather connection 68 with a tubular shaft 100 70, journaled upon the tubular shaft 54 and resting upon a flange 72 fixed to said tubular shaft 54.

The shaft 4, carrying the table 10, is provided at its upper end with a bevel gear 82 105 meshing with a bevel gear 84, fixed upon a drive shaft 86 journaled in bearings 88 on top of the frame 2 and provided with fixed and loose pulleys 90 and 92, respectively.

The tubular shaft 54 is provided at its 110

upper end with a bevel gear 94 intermeshing with a bevel gear 96 fixed upon a counter shaft 98 provided with another bevel gear 100, intermeshing with a bevel gear 102 fixed upon a vertical shaft 104 provided at its upper end with a bevel gear 106 driven by a bevel gear 108 loosely mounted upon the drive shaft 86.

10 The tubular shaft 70 is provided at its upper end with a bevel gear 110 intermeshing with a bevel gear 112 fixed upon a counter shaft 114 provided with another bevel gear 116 driven by a bevel gear 118 fixed upon the lower end of the vertical shaft 104, which is journaled in a bracket 120 depending from the frame 2. The counter shafts 98 and 114 are journaled in hangers 122 and 124 depending from the upper portion of the frame 2. The bracket 122 carries the segment 80 and is provided with a bearing 126 surrounding the tubular shaft 70.

The bevel gear 108 is loosely mounted upon the drive shaft 86 but may be caused to rotate therewith at will, through the intermediacy of a clutch 130 having a groove and feather connection 132 with the drive shaft 86 and controlled by a hand lever 134.

202 designates a sweep of ordinary type for packing the ore upon the table 10 and forcing the water to the top of said ore. The pole of the sweep 202 is secured in brackets 204 removably fixed to the conical distributor 52.

35 In the practical operation of the machine the distributor 52 is equipped with one or more sweeps 202. The gates 24 are then adjusted to lowered position, while the clutch 130 is shifted into engagement with 40 the bevel gear 108 to drive the distributor 52 and the hopper 62 in reverse directions to each other through the intermediacy of the intervening gearing when power is applied to the fixed pulley 90. The table 10

45 is driven in the same direction as the hopper 62 through the intermediacy of the gears 84 and 82. The crushed ore is conducted to the hopper 62 by a chute or other suitable conveyer (not shown) and as said hopper 62 rotates, it discharges the ore upon the distributor 52, which discharges it uniformly upon the table 10. As the ore falls upon the distributor 52 the guard 58 prevents said ore from being cast off by centrifugal force and directs it downwardly around the drum 50 from where it spreads over the table 10. As the crushed ore and the accompanying water flow outwardly upon the table 10 towards the rim 16, the 55 water is forced to the top and escapes through the spouts 26 which are raised slightly in advance of the rising ore through the intermediacy of the gates 24 and their respective actuating mechanisms embodying 60 the screws 30 and the nuts 28. After the 65

ore attains the desired depth upon the table 10 the belt is shifted from the tight pulley 90 to the loose pulley 92 to bring the moving parts to a stop. The table 10 is then unloaded.

Any number of levers 36 may be spaced around under the table 10 to effect the opening and closing of the gates 24 at the desired speed.

From the above description it will be apparent that I have produced an ore concentrator which can be operated at a minimum cost of labor by employing the automatic slide gates 24, and while I have illustrated and described the preferred embodiment of my invention, it is obvious that such changes in the form, detail construction and arrangement of parts may be made, as properly fall within the scope of the claims. 75 80

Having thus described my invention, what I claim and desire to secure by Letters Patent, is:

1. In an apparatus of the character described, a rotary table, gates operably mounted on said table and provided with spouts, screw mechanism rotatable with the table for opening and closing said gates, and means independent of the table which said screw mechanism contacts and is actuated thereby during each revolution of the table. 90 95

2. In an apparatus of the character described, a rotary table, a gate operably mounted on said table, a nut fixed to said gate, a screw threaded into said nut, a bearing fixed to the table and carrying said screw, a wheel fixed to said screw to rotate the same, a lever adapted to be adjusted to one position to rotate said wheel in one direction to open the gate and to another position to rotate the wheel in a reverse direction to close the gate, and a stationary support for said lever. 100 105

3. In an apparatus of the character described, a rotary table, a gate operably mounted on said table, a nut fixed to said gate, a screw threaded into said nut, a bearing fixed to the table and carrying said screw, a wheel fixed to said screw to rotate the same, a lever having two prongs and adapted to be adjusted to bring one prong in the path of one side of the wheel to rotate the same in a direction to open the gate and adjusted to bring the other prong in the path of the other side of the wheel to rotate the same in a direction to close the gate, and a support for said lever. 110 115 120

4. In an apparatus of the character described, a rotary table embodying an upwardly extending wall having an opening 125 therein, a gate associated with the wall and arranged to slide up and down to, respectively, cover and uncover said opening, and mechanism for lowering said gate step by step as the table rotates. 129

5. In an apparatus of the character described, a rotary table embodying an upwardly extending wall having an opening therein, a gate associated with the wall and arranged to slide up and down to, respectively, cover and uncover said opening, screw mechanism for actuating said gate, and means independent of the table which said screw mechanism contacts and is ac-

tuated thereby during each revolution of 10 the table.

In testimony whereof, I affix my signature in the presence of two witnesses:

MARY R. ARTHUR,
Executrix of James B. Arthur, deceased.
